DESIGN FOR A NAME PLATE

Winford L. Enghauser, Cincinnati, Ohio, assignor to The Production Plating Works, Inc.,
Lebanon, Ohio, a corporation of Ohio

Application June 22, 1942, Serial No. 107,303

Term of patent 14 years

To all whom it may concern:

Be it known that I, Winford L. Enghauser, a citizen of the United States, residing at Cincinnati, in the county of Hamilton and State of Ohio, have invented a new, original, and ornamental Design for a Name Plate, of which the following is a specification, reference being had to the accompanying drawing, forming a part thereof.

I claim:

The ornamental design for a name plate substantially as shown.

WINFORD L. ENGHAUSER.
